Primary Examiner — Prabhakar Deshmukh(74) *Attorney, Agent, or Firm* — Kelly & Kelley, LLP(57) **CLAIM**

The ornamental design for a handle, as shown and described.

DESCRIPTION

FIG. 1 is a front perspective view of a handle showing our new design;

FIG. 2 is a rear perspective view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a top plan view thereof.

The broken lines are included for purpose of showing environmental context of the design and form no part of the claimed design.
